(57) **CLAIM**

The ornamental design for a pedometer, as shown and described.

DESCRIPTION

FIG. 1 is a front, top, perspective view of the embodiment of a pedometer showing our new design;

FIG. 2 is rear, top, perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a front, top, perspective view showing a condition in which the body is opened thereof;

FIG. 10 is a rear, top, perspective view showing a condition in which the body is opened thereof;

FIG. 11 is a front elevational view showing a condition in which the body is opened thereof;

FIG. 12 is a rear elevational view showing a condition in which the body is opened thereof;

FIG. 13 is a top plan view showing a condition in which the body is opened thereof;

FIG. 14 is a bottom plan view showing a condition in which the body is opened thereof;

FIG. 15 is a right side elevational view showing a condition in which the body is opened thereof; and,

FIG. 16 is a left side elevational view showing a condition in which the body is opened thereof.

The broken lines are shown in the views for illustrative purpose only, and form no part of the claimed design.
